UNITED STATES PATENT OFFICE

JOHN M. HOTHERSALL, OF BROOKLYN, NEW YORK, ASSIGNOR TO AMERICAN CAN COMPANY, OF NEW YORK, N. Y., A CORPORATION OF NEW JERSEY

METHOD OF MAKING CONTAINER CLOSURES

Application filed June 23, 1928. Serial No. 287,862.

My invention relates in general to container closures and the method of making the same, and has more particular reference to a multipart closure made from a one piece blank.

An object of my invention is the provision of a method for producing such a multipart closure from a one piece blank in an economical manner without any spoilage or waste and by a minimum number of operations.

Another object of my invention is to make a closure made by the aforementioned method, which, by slight modifications in its construction and in the method of making the same, can be adapted to a variety of different containers and in a variety of different combinations.

Numerous other objects and advantages of the invention will be apparent as it is better understood from the following description, which, taken in connection with the accompanying drawings, discloses a preferred embodiment thereof.

Referring to the drawings:

Figure 1 is a perspective view of one form of container in which my invention is embodied;

Fig. 2 is a perspective view of the finished parts of the container and the closure elements as they appear after the seal has been broken;

Fig. 3 is a perspective view of the blank used for forming the two parts of the closure shown in Figs. 1 and 2;

Fig. 4 is a fragmental vertical sectional view of the blank after it has been altered by the first operation;

Fig. 5 is a view similar to Fig. 4 illustrating the second operation,—that of severing the altered blank into two parts;

Fig. 6 is a fragmental vertical sectional view illustrating the inner element of the closure after the third and final operation has taken place;

Fig. 7 is a fragmental vertical sectional view of the upper parts of the container and the closure elements after the seal has been formed between the container and closure elements;

Fig. 8 is a fragmental vertical sectional

view of the die parts used in the first operation to obtain the result illustrated in Fig. 4;

Fig. 9 is a fragmental vertical sectional view showing portions of a cutting die for severing the altered blank into two closure elements and obtaining the results disclosed in Fig. 5;

Fig. 10 is a fragmental vertical sectional view of parts of the forming die for finally forming or curling the inner element of the closure and obtaining the results disclosed in Fig. 6, and

Fig. 11 is a fragmental vertical sectional detail of a completed closure embodying my invention in a slightly modified form.

To illustrate a preferred embodiment of my invention, I have shown in the drawings a conventional type of container comprising a cylindrical body 11 of sheet metal having a side seam 12 and a bottom end double-seamed 70 or otherwise permanently secured thereto.

A short distance below the top of the container body 11, the annular wall of the body is bent or beaded inwardly to form an outward, annular groove or depression 14. Just 75 above this depression 14, the metal of the body continues straight upwardly at 15 and is then bent inwardly, downwardly and outwardly to form a rounded container top or curl 16. The inwardly extending curved top part of the curl 16 forms a supporting seat 17, and the downwardly extending curved inner part of the curl 16 forms a friction seat 18 for the inner element of the closure yet to be described in detail.

Reference numeral 19 indicates the blank from which my improved two piece closure (shown in Fig. 2) is to be formed. This blank 19 consists of a flat, circular disc of sheet metal having a tongue extension 20 with a perforation 21 therein and a tearing notch 22 at the meeting point of the periphery of the circular disc and one side of the tongue extension 20.

To form my improved two-piece closure, namely, an inner closure element 50 and an outer sealing band or ring 60, the blank 19 is placed in a suitable die mechanism (shown in Fig. 8) consisting of a lower die member 23, upper die member 24 and an annular die

ring 25. By this first die operation, the blank 19 is formed into the shape shown in Fig. 4, resulting in a cup-shaped member having a horizontal, circular, depressed bottom or panel 26, a vertical annular wall 27, and an outwardly and downwardly curved part 28 terminating into an annular vertical part 29 parallel with the vertical wall 27.

This partially formed or altered closure blank is then subjected to the second die operation (illustrated in Fig. 9). This die mechanism consists of a lower supporting chuck 30 having a supporting part 31 of substantially the same configuration as the inside surface of parts 27, 28 and 29 of the altered blank, an upper complementary annular clamping chuck 32 and a cutting die 33 having a sharp cutting edge 34 adapted to engage and cut the one-piece altered closure blank along the annular line of severance 35, which line is located at the junction of the parts 27 and 28. This cutting operation results in two closure elements, namely, the partially formed inner element or cover 50 and the finished outer element or sealing ring or band 60.

The partially formed inner closure element or cover 50, with its straight wall 27, is now ready to be subjected to the third and final operation. For this purpose it is placed in the die mechanism shown in Fig. 10, which comprises a lower chuck 38 for supporting the bottom or panel part 26 of the inner closure member 50, an upper clamping chuck 39, a lower curling die 40 and an upper curling die 41. The substantially straight part 27 of the partially formed inner cover 50 is held between the side walls of the lower and upper curling dies and when the two die parts come together, the upper part of the straight wall 27 is curled into an annular arched flange 42 (shown in Fig. 6), which completes the formation of the inner closure member 50. This inner closure member 50 together with the outer closure member or sealing band 60 may then be assembled to the container body 11 to close the same (as illustrated in Fig. 7).

If an hermetic seal is desired, any suitable lining or packing material 43 may be interposed between the body curl 16 and the inner closure curl or flange 42. This may be done by applying the packing material 43 to the annular concavity of the cover curl 42 before the same is applied to the can body 11. When the container body 11 is to be finally sealed, the cover 50, with or without the packing material 43, is applied to the top of the container body 11 so that the curled flange 42 of the cover comes to lie over the top 17 of the body curl 16, and the wall 27 of the cover 50 frictionally engages the curved part 18 of the body curl 16. The outer closure or annular locking ring 60 is then placed over the cover 50 so that the curled flange 28 of the ring 60

engages with the curled flange 42 of the cover 50 and the straight depending annular wall 29 of the ring is then bent inwardly by any suitable closing mechanism until the lowermost edge of the part 29 lies within the annular depression 14 of the container body 11. This results in a very tight closure for the container body 11.

As stated in the first part of this specification, the principle of my invention is applicable to a variety of different forms of containers and in a variety of different combinations. Fig. 11 illustrates one such modified form of my invention. Here the container body 11 is not depressed near the top and instead of an inward curl has its top formed into an outward curl or bead 44. The packing 43 and the outer closure or ring 60 are substantially the same as the corresponding parts shown in Fig. 7. The cover 50 has a friction wall part 45 which closely hugs and runs parallel with the body wall 11 and thence the material of the cover is rebent upon itself at 46 to form a vertical wall 47 and is again bent at 48 at right angles to the vertical wall 47 to form a raised horizontal panel 49. All these modifications are accomplished by a suitable change in die construction and action, which need not be illustrated or described in detail for a complete understanding of my invention.

From the foregoing it will be readily appreciated that my invention is not limited to the exact construction of the container tops and covers or the exact shape of the sealing bands illustrated in the drawings.

To open my container, its only necessary to grasp and pull the tearing tongue 20 outwardly and upwardly, or preferably a nail or other sharp instrument may be inserted into the hole 21 of the tongue 20 to assist in the pulling action. The notch 22 will then assist in starting a line of severance across the metal of the band. Fig. 2 shows the sealing band severed adjacent the tearing tongue 20.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. The method of producing a multipart closure for containers from a one-piece blank without spoilage or waste, which consists in subjecting a flat blank to a forming operation whereby the blank is altered into a form which contains the closure elements, ultimately to be produced, in partially formed condition, then subjecting this altered blank

to a cutting operation resulting in an unfinished closure element and a finished closure element, then subjecting the unfinished closure element to another forming operation to produce a second finished closure element.

- 5 2. The method of producing a multipart closure for containers from a one piece blank without spoilage or waste, which comprises dividing a closure blank into inner disk and outer ring parts, forming said inner and outer parts into a disk with a shoulder and edge flange and a U-shaped ring respectively for overlapping relation at the seam to the container body and compressing said parts to form said seam with the outer part embracing the inner part and the edge of the body wall.

- 10 3. The method of producing a multipart closure for containers from a one piece blank without spoilage or waste, which consists in subjecting a flat blank to a forming operation whereby the blank is altered into a form which contains the closure elements, ultimately to be produced, in partially formed 25 condition of an outside U-shaped ring and an inner flat plate, then subjecting this altered blank to a cutting operation resulting in an unfinished central closure plate element and a finished outer U-shaped ring closure element, then subjecting the unfinished central closure element to another finishing operation producing an edge flange therearound.

- 30 4. The method of producing a multipart closure for containers from a one piece blank without spoilage or waste of material, which 35 consists in subjecting the material from which the closure parts are to be made to a forming operation which results in a form of the material containing the multiple closure parts, ultimately to be produced, in partially 40 finished condition, subjecting the said form to a severing operation resulting in an unfinished closure part and a finished closure part, and finally subjecting said unfinished 45 closure part to another finishing operation.

- 50 5. The method of sealing a container which consists in forming a circular blank with a marginal part having an inner shoulder and an outer depending flange and with a central plate part; then severing said parts on a circular line so as to leave said central part with a central plate and an upstanding shoulder and to leave said marginal part with an inwardly extending flange and an outer 55 depending flange; then pressing and drawing outwardly the upper part of said upstanding shoulder of the central part; then applying the latter on the mouth of a container having an outer shoulder, with said marginal part 60 superposed on said central part; and then pressing said parts to the container and bending said depending flange to engage under the shoulder of the container.

JOHN M. HOTHERSALL.
